UNITED STATES PATENT OFFICE.

HENRY M. CHILDERS, OF ONTARIO, OREGON, ASSIGNOR OF THREE-FOURTHS
TO EMMA J. SMITH AND HELEN S. CHILDERS, OF SAME PLACE.

NEEDLE-THREADER.

SPECIFICATION forming part of Letters Patent No. 638,701, dated December 12, 1899.

Application filed November 24, 1896. Serial No. 613,278. (No model.)

To all whom it may concern:

Be it known that I, HENRY M. CHILDERS, a citizen of the United States, residing at Ontario, in the county of Malheur and State of Oregon, have invented certain new and useful Improvements in Needle-Threaders; and I do hereby declare the following to be a full, clear, and exact description of the invention, such as will enable others skilled in the art to 10 which it appertains to make and use the same.

My invention relates to certain new and useful improvements in needle-threaders for sewing-machines, the object of the same being to provide a simple and cheaply-constructed device of this character by means of 15 which the needle of the sewing-machine may be readily and conveniently threaded even by persons with poor eyesight.

The invention consists of a block having a 20 cut-away portion on its under side permitting it to straddle the presser-foot of a sewing-machine, a cut-away portion on its upper side forming a shoulder at one end, a tapering cone-shaped slot extending laterally there- 25 through having an extension at one side leading outwardly through said shoulder, and a recess to receive the point of the needle.

The invention is clearly illustrated in the accompanying drawings, in which—

30 Figure 1 represents a perspective view of a sewing-machine, showing the application of my improved threading device thereto. Fig. 2 is a detail perspective view, on an enlarged scale, of the thresher. Fig. 3 is a vertical central longitudinal section through the same. Fig. 4 is a top plan view, and Fig. 5 is a horizontal sectional view, through the tapering opening therein.

Like reference-numerals indicate like parts 40 in the different views.

My improved thresher is made up of a block 1, of metal or other suitable material, having its under side cut away, as shown at 2, forming legs or supports 3, upon which said block 45 is adapted to rest and permitting the same to straddle the presser-foot 4 of the sewing-machine 5. The upper side of the block 1 is cut away at one point, forming a shoulder 6 and a lug or extension 7 thereon. Extending

through the lug 7 is a tapering cone-shaped 50 opening 8, which terminates at a point adjacent to the shoulder 6 and has a slit 9 leading thereto through the lug or extension 7. A vertically-disposed recess 10, adapted to receive the lower end of the needle 4, is formed 55 in the top surface of the block 1 adjacent to one side of the shoulder 6.

In using my device the block 1 is applied as shown in Fig. 1 of the drawings and the needle 4' is lowered so that the point thereof fits with- 60 in the recess 10. The said needle is moved until the eye therein lies directly opposite the small end of the tapering opening 8. The thread is then free to be passed through said opening and through the eye of the needle, 65 being guided in its course by the inclined sides of said tapering opening. When inserted in the eye of the needle, the thread may be withdrawn from the slot 8 through the slit 9, leading thereto. The needle 4' is then 70 moved out of the recess 10 and the block 1 is removed.

The device is extremely simple in construction, can be cheaply made, and is effective for the purpose for which it was designed. 75

Having now described my invention, what I claim as new, and desire to secure by Letters Patent, is—

As a new article of manufacture, a needle-threader comprising a parallelogrammic 80 block having a cut-away portion upon its lower surface to straddle the presser-foot of a sewing-machine, a lug upon the upper surface of the block at one extremity thereof, a tapering opening extending through the lug 85 terminating at a point above the depressed surface of the block, a slit extending from the opening through the lug, and a recess in the block for receiving the point of the needle opposite the contracted end of the tapering 90 opening, substantially as described.

In testimony whereof I have signed this specification in the presence of two subscribing witnesses.

HENRY M. CHILDERS.
